BUILDING PANEL

John Meslin, Brooklyn, N. Y.

Application December 18, 1939, Serial No. 309,876

2 Claims. (Cl. 189—36)

My invention relates to buildings, and has among its objects and advantages the provision of an improved sheet metal panel.

An object of my invention is to provide a sheet metal panel which may be anchored to the ceiling or walls through the medium of nails, and in which the panels may be arranged partly in overlapping relation and nailed to the supporting structure, with the nail heads terminating flush with the outer faces of the panels.

A further object is to provide a sheet metal panel which may be nailed to a supporting structure and in which novel means are incorporated to the end that the nail heads may be driven flush with the outer faces of the panels without buckling or otherwise distorting the panels.

In the accompanying drawing:

Figure 1 is a view illustrating my panels applied to a ceiling;

Figure 2 is a sectional view of the structure illustrated in Figure 1;

Figure 3 is a perspective view of one of the panels;

Figure 4 is an enlarged perspective view of one corner of the panels;

Figure 5 is a sectional view of the panels applied to a wall illustrating the manner in which the panels are provided with backing to resist distortion; and

Figure 6 is an enlarged sectional detail view of an overlapped joint between two wall panels.

In the embodiment selected to illustrate my invention, Fig. 3 illustrates a sheet metal panel 10 offset along two marginal edges to provide flanges 12, which lie in a common plane paralleling the area 14. The two other marginal edges are bent back upon themselves to provide flanges 16, which are spaced from the area 14 to receive filler strips 18. Filler strips 18 may comprise any suitable material such as cardboard and constitute a backing which prevents collapsing of the flanges 16 and the areas 14 when the panels are nailed to the supporting structure.

Flanges 12 are provided with large openings 20 spaced at suitable intervals, the spacing depending upon the number of nails to be used for a given panel. Referring to Fig. 1, the area 14 is provided with a series of small openings 22 along the margins under which the flanges 16 lie, and the openings 22 are spaced exactly as the openings 20 so that one series of openings 22 will register with the underlying series of openings 20 in the underlying flange 12 of an adjacent panel.

Fig. 3 illustrates a rear view of the panel 10, which face of the panel lies adjacent the ceiling, with one flange 16 overlying one flange 12 on a previously laid panel. Flanges 12 are cut diagonally at 24 so as to permit close nesting of the panels, as illustrated in Fig. 1. The panels, when being laid, may be temporarily fastened to facilitate permanent nailing by driving small nails 25 through the flanges 12.

When the panels are laid according to Fig. 1, the openings 22 will accurately register with the openings 20 in the underlying flanges 12. Finishing nails 26 are then driven in the openings 22, through the filler strips 18 and the flanges 16, through the large openings 20 and into the supporting structure 28. Since the flanges 16 are imperforate, driving of the nails 26 through these flanges will form burrs 30 which bend into the openings 20 and form keys which prevent relative lateral shifting between the panels. Thus, the openings 20 provide accommodation for the burrs 30.

Openings 22 are of such diameters as to fit snugly about the heads 32 of the finishing nails 26, and the nails are driven to bring the faces of the heads flush with the outer faces of the panels 10. Strips 18 provide effective backing for the areas 14 of the panels 10 so as to protect the areas against buckling or permanent distortion should the hammer strike the panels. The openings formed in the flanges 16 when the nails are driven therethrough fit tightly on the nails which provides an anchorage which firmly supports the panels relatively to each other and with respect to the supporting structure 28.

Flanges 12 are nailed firmly against the supporting structure 28, while the flanges 16 provide reinforcement and rigidity so that the corresponding margins of the panels are brought into effective pressure relation with the underlying flanges 12 to provide a dustproof joint. For ceiling covering purposes, filler strips 18 are of a width corresponding to the width of the flanges 16, and the areas 14 of the panels are spaced from the adjacent face of the support 28.

In covering walls, it is preferable to provide a filler 34 for the entire area 14, as illustrated in Fig. 5 so as to afford effective backing for the panels. Filler 34 may comprise fiber board. Thus, the relatively thin sheet metal panels which provide the wall covering are backed in such manner as to resist denting and buckling so as to maintain a perfectly smooth surface. Filler strips 18 will, of course, be inserted be-

tween the flanges 16 and the corresponding margins of the area 14.

Flanges 16 are so spaced from the area 14 as to bring the outer face of one area 14 flush with the corresponding face of an adjacent panel when the flanges 16 are positioned over the underlying flanges 12. Thus, the panels or areas 14 are positioned in abutting relation throughout the wall or ceiling, with the outer faces of the areas 14 lying in a common plane. Openings 20 are of sufficient diameters to provide ample accommodation for the burrs 30 so as to eliminate separation of the overlapping parts, particularly with respect to the flanges 16 on the underlying flanges 12.

Having thus described certain embodiments of my invention in detail, it is, of course, understood that I do not desire to limit the scope thereof to the exact details set forth except in so far as those details may be defined in the appended claims.

I claim:

1. A building panel having an offset flange and a nailing flange bent back upon the panel but spaced therefrom, said panel being provided with nail receiving openings opposite said nailing flange, filler means positioned between said nailing flange and the panel, said offset flange being provided with openings and adapted to underlie the nailing flange of an adjacent panel, with the openings in the offset flange aligning with the nail receiving openings in the

overlying panel, the nail receiving openings in said panel being of such diameters as to fit about the peripheral contour of the heads of nails driven through the nailing strip to bring the heads of the nails flush with the panel, the openings in said offset flange being larger than the diameter of the nail to provide spaces for burrs formed on said nailing flange when the nails are driven therethrough.

10 2. A building panel having offset flanges and nailing flanges bent back upon the panel but spaced therefrom, said panel being provided with nail receiving openings opposite said nailing flanges, filler means positioned between said nailing flanges and the panel, said offset flanges being provided with openings and adapted to underlie the nailing flanges of adjacent panels, with the openings in the offset flanges aligning with the nail receiving openings in the overlying panels, the nail receiving openings in said panel being of such diameters as to fit about the peripheral contour of the heads of nails driven through the nailing strip to bring the heads of the nails flush with the panels, the openings in said offset flanges being of larger diameters than the nails to provide spaces for burrs formed on the nailing flanges when the nails are driven therethrough, said burrs fitting snugly inside the openings in said offset flanges to restrain the overlapped panels from relative shifting.

JOHN MESLIN.
